UNITED STATES PATENT OFFICE.

OTTO F. PAEHLKE, OF CLEVELAND, OHIO.

MOLDING APPARATUS.

966,762.

Specification of Letters Patent.

Patented Aug. 9, 1910.

Application filed December 3, 1909. Serial No. 531,168.

To all whom it may concern:

Be it known that I, OTTO F. PAEHLKE, citizen of the United States, residing at Cleveland, in the county of Cuyahoga and 5 State of Ohio, have invented certain new and useful Improvements in Molding Apparatus, of which the following is a specification.

My invention relates to improvements in 10 molding apparatus, and the improvement consists in the combination of parts, substantially as herein shown and described and more particularly pointed out in the claims.

My object is to take conditions in the 15 foundry as I find them and furnish the molder with a device wherewith he can do better work and save time and labor on each and every job regardless of the run of the day's work. By this last I mean that patterns of all kinds and shapes and sizes may 20 be handled as they come and that only one mold, or many, may be made from a single pattern with economy and despatch and without special preparation. To this end, I 25 provide a set of devices adapted to be detachably and adjustably secured to molders' patterns to coöperate with the ordinary molders' flasks in general use, and wherewith the pattern may be steadied and guided 30 when withdrawn from the mold to prevent distortion or breaking down of the mold.

In the accompanying drawings, Figure 1 is a sectional view of a flask and mold and pattern substantially completed and as it appears 35 before the cope is lifted and removed, and Fig. 2 is a similar view of the same parts without the cope. Fig. 3 is a sectional view of the lower half of the flask and mold with my improved steady-pins attached to the pattern and in position to guide the pattern for removal, the dotted lines showing the pattern in raised position. Fig. 4 is a 40 sectional view of the flask and mold complete without the pattern and ready for casting operations. Fig. 5 is a perspective view of the lower half of the flask and mold with the pattern therein and showing my improved devices operatively connected therewith. Figs. 6, 7 and 8 are perspective 45 views of one form of steady-pin, thumb screws and screw plate, respectively, as sold to the trade.

As shown, my invention comprises two or more right angled members A, which may properly be referred to as steady-pins in view of their function and purpose. Each member consists of a flat arm 2 having a longitudinal slot 3 at one end and an integral stem 4 at right angles at its other end. Stem 4 is round, triangular, square or of any suitable cross section and relatively of less length than arm 2. However, as to the length of these parts no particular limitation is intended, but for general use a length of twelve inches for arm 2 and ten inches for stem 4 is sufficient to meet the average requirements in a foundry. When in use, arms 2 overlap the top end edges of the lower half or so-called drag 5 of the flask B and rest flush upon or freely above the mold 70 C and pattern D when the upper half or so-called cope 6 of the flask is removed. Stem 4 is placed at the outside of the flask and projects through or is slidably confined within open lugs or keepers 7, such as are always found at the ends of one part of flask B. Keepers 7 also co-act with and slidably hold the fixed pins 8 on the other part of the flask to keep these parts in matching relation during the making of the mold and during casting operations thereafter and they also serve to steady the cope or upper flask part when removed and replaced. Now, every foundry, especially where floor work is done, has a large assortment of flasks of various dimensions to meet varying needs in making molds, and in practice no larger flask is used than any given pattern or mold requires. This invariably brings the pattern close to the edge of the flask, especially at opposite ends thereof, whether the job be large or small, and permits the use of my steady-pins A with the lugs 7 of any flask of ordinary construction and without change in either the flask or pattern. However, a plate or set of plates 9 are preferably supplied which may be fastened upon, or inset into the pattern, or upon its rapping board, by screws 10 or otherwise, and this fastening may be temporary or permanent and be placed where most convenient for attaching steady-pins A. To this latter end, each plate 9 is provided with a screw hole 11 to receive a thumb screw 12 which is of a size

to pass through slot 3 of arm 2. By slotting said arm, no great care need be exercised in placing plates 9 upon the pattern, as all variation in distance and alinement between 5 the pattern and the end of the flask may be adjustably taken up by the accommodation afforded to thumb-screws 12 within said slot. Again, after tamping of the cope part of the mold and when the level of the pattern may 10 have lowered somewhat in respect to the original parting line as often occurs, I can introduce metal washers W of any suitable thickness between arms 4 and plate 9 to make a rigid attachment for steady-pins A. This 15 adaptation of the device brings out an important point of difference between my invention and all other molding apparatus or attachments known to me, to wit,—that with my device a molder is enabled to attach and 20 detach the same from the pattern without altering the flask or the mold and without having said device take any part or place in the making of the mold until the pattern is to be withdrawn. Thus my steady-pins for 25 the pattern are not subjected to tamping operations during the making of the mold, nor are they embedded in the mold or in the top edges of the flask, but are absolutely free therefrom, and therefore may be attached 30 and detached without danger of distorting or breaking down the mold and causing the need of after building up or repairs thereon.

In practice, my steady-pins are attached 35 after the mold has been completely tamped in both cope and drag and after the cope has been removed. They do not form supports for the pattern during tamping operations as this is objectionable for the reason that when the cope is tamped there is always 40 great liability of the pattern and mold in the drag to settle and if the attachments A were in place at this time, a slight spring or yield would result which would distort or enlarge the mold. A spring or shift in the 45 pattern due to tamping, causes the mold to break down or crumble here or there, or if this does not actually occur, a change or distortion would still be the result to the detriment of the mold and the final casting. 50 I avoid all the foregoing objections by constructing my improved attachment as hereinbefore described and by using the same as follows: Following usual practices and well known methods I first build up the mold to the form shown in Fig. 1, wherein 55 the cope or upper half of flask B is ready for removal from the lower half. The cope being removed, the next step is to withdraw the pattern, always a delicate task, especially when the mold is of large size 60 and because the usual practice is to place the more difficult work in the drag. Therefore great care and skill must be required in this operation, otherwise the mold will be 65 distorted, changed, or broken down, thus

occasioning loss of time and exacting labor to repair the mold. To meet the emergency, I now place my steady-pins A in the open lugs or keeper 7 on the lower flask, and firmly fasten arms 4 to the pattern by thumb 70 screws 12, using washers W between screw plates 9 and arms 4 if the pattern has settled during previous tamping operations. This being done, steady-pins A may now be regarded as fixed and rigid parts of the pattern. Screw eyes 15 are also usually screwed 75 into the pattern at this time to lift the pattern from the mold, and in a large pattern four screw eyes are used, two at each end. The pattern is now raised slowly and carefully, rapping of the pattern proceeding 80 also as usual. Steady-pins A now guide and hold the pattern to a fixed vertical travel and prevent accidental shifting of the pattern and obviously greatly facilitate the 85 making of a perfect mold. When the pattern is finally withdrawn and laid aside, the cope is replaced, other foundry practices perhaps being performed in the meantime. The steady-pins A are now detached, and 90 the pattern again used for another mold if desired, but in no event do steady-pins A remain on the pattern during any part of the molding operations except for the brief interval when the pattern is withdrawn. 95

Fig. 6 represents a slight modification of the steady pin member and particularly in the portion indicated by 4', which is substantially V shape in cross section.

What I claim is:

1. A molder's flask having lugs at its ends, and a pattern, in combination with a set of steady-pins comprising right angled members having adjustable and detachable connections with said pattern and having stem portions to slidably engage said lugs. 100

2. A divided flask having pins and keepers therefor on its respective parts, and a pattern, in combination with right angled members having adjustable and detachable fastening connections for said pattern and having projecting stems adapted to slidably engage within said keepers. 110

3. A molder's flask having steady-pin lugs thereon, and a pattern having detachable plates, in combination with right angled steady-pin members having detachable fastening connections for said plates and pattern and constructed with stems to slidably engage said flask lugs. 115

4. A molder's flask having steady-pin lugs thereon, and a pattern having fastening plates for steady-pins, in combination with a set of steady-pins having slotted arms and right angled stems, and thumb screws to fasten said steady-pins to said plates and pattern. 120

5. As an article of manufacture and sale, an attachable and detachable device for safeguarding molds during withdrawal of pat- 125

terns, comprising a right angled member, an attachable pattern plate, and a clamping device for said member and plate.

6. An attachable and detachable device for safeguarding molds during withdrawal of patterns, comprising steady-pin members having slotted arms and fixed stems at right angles thereto, combined with thumbscrews

to detachably fasten said slotted arms rigidly to the pattern.

In testimony whereof I affix my signature in presence of two witnesses.

OTTO F. PAEHLKE.
